STEAM ACTUATED ROTARY DRILLING CONTROL

Original application filed December 10, 1927, Serial No. 239,143. Divided and this application filed June 24, 1929. Serial No. 373,370.

This application is a division of my co-pending application entitled Steam actuated automatic drilling control, filed December 10, 1927, under Serial No. 239,143.

5 The primary purpose of my invention is to provide means for automatically feeding rotary well-boring tools at such rate that the drilling effect by such tools, and the torsional stress on the drill pipe by which they 10 are rotated, shall be substantially constant.

In drilling wells by the rotary method the drill bit is kept in constant revolution on the bottom of the hole by means of a string of 15 drill pipe through which a stream of mud-laden fluid is conducted to the bottom of the hole, this fluid washing away the bit cuttings and carrying them to the surface outside of the drill pipe. This pipe is revolved by a rotary table geared to a suitable source 20 of power, a squared pipe or "Kelley joint" passing through a corresponding opening in the rotary table and being screwed to the upper end of the drill pipe string.

The entire weight of the drill string cannot 25 be allowed to rest on the bit—which cuts on its end face only—as the great weight of such string in even a relatively shallow hole would lock the bit solidly on the bottom, causing the pipe to be twisted off if the rotative effort 30 at the upper end of the string were continued.

The drill pipe is therefore suspended from the upper part of the derrick by means of a wire line rove through a pair of multiple 35 blocks (crown block and travelling block), one end of this line being spooled on a winding drum with brakes, by the rotation of which the drill string is raised or lowered. The opposite end of the line may be dead-ended, but is more commonly spooled on the 40 calf wheel drum, from which it may be paid out as required. Suitable intermediate connections, such as a hook attached to the lower or travelling block, a swivel, and an elevator clamped around the upper end of the 45 drill string, permit the latter to rotate while the block and lines retain a substantially fixed position.

In drilling by the rotary method the rate 50 of progress in depth, for any given hardness

of the material being penetrated by the bit, will vary directly with the downward pressure exerted on the bit. As this pressure is necessarily less than that exerted by the weight of the drill string, the rate will vary 55 inversely, for any given weight of string, with the load carried by the feeding unit, which may be varied at will by the operator. The pressure which may be exerted on the bit is limited, in most cases, solely by the ability 60 of the drill string to withstand the torsional stress set up by the resistance of the material being penetrated to the action of the bit, the pipe twisting off if this limit be exceeded. It follows that the highest rate of progress 65 (the "most hole") will be made when the bit is caused to exert a constant pressure on the bottom of the hole, this being the pressure which will set up the highest torsional stress which the drill pipe will carry with 70 safety.

In rotary drilling without the use of any kind of automatic control the rate of feed is controlled manually by the operator, who releases a small amount of line from the 75 winding drum at short intervals, thus paying the drill string downward. During these intervals the elasticity of the line and other parts of the supporting mechanism continue to lower the bit at a decreasing rate until it 80 substantially ceases to make hole. The disadvantages of such manual control are evident. The bit can operate at its maximum pressure and efficiency only during an exceedingly brief period after paying out line, and an error in judgment by the operator in 85 releasing too much or too little line will either freeze the bit and cause a twist-off or will sustain the bit at too low a pressure, causing inefficient operation. The operator having 90 no guide to torsional stress other than the growl of the drive gearing, the speed of the prime mover or similar phenomena having only a loosely indicative value, and a twist-off being an expensive and painful occurrence, is likely to keep on the safe side by 95 keeping the torsional stress and bit pressure at all times below the maximum.

It follows that, in spite of the greatest skill and vigilance, manual control cannot 100

possibly make hole at anywhere near the rate obtainable where the feed is definitely controlled by the torsional stress in such manner that the latter may be maintained 5 constant at its safe maximum.

To overcome these disadvantages of manual control many automatic or semi-automatic devices have heretofore been proposed, such for instance as various applications of 10 differential gearing, hydraulic jacks controlled by levers or other mechanical linkage, and devices in which the weight of the drill string is partially supported by the pressure of the mud-laden fluid circulated there- 15 through.

All these devices are burdened by excessive complication. The differential gear apparatus is responsive and dependable, if properly designed, but is almost prohibitively 20 expensive both as to first cost and maintenance and is not readily adaptable to existing, nearly standardized drilling machinery. The hydraulic systems heretofore proposed are not sufficiently responsive, are liable to 25 failure from unforeseen causes, and are too costly to be practicable. The floating devices are relatively cheap but fail completely in any case of loss of fluid due to penetration of a porous stratum, and fail to maintain the 30 requisite constant pressure on the bit.

In my invention these objections are largely overcome by the use of a hydraulic suspension for the drill string, so arranged that the pressure of the fluid in the hydraulic 35 cylinder is governed by an automatic distribution of the steam supplied to the engine driving the rotating mechanism. Because of its extreme simplicity in all of its various forms this arrangement is cheap and readily 40 maintained, is dependable as to the maintenance of a constant pressure on the bit, is sharply responsive to changes in character of material encountered, and is readily adapted to any steam driven rotary drilling 45 unit (to which its usefulness is restricted) without departing in any particular from standard construction.

My basic invention—the control of pressure in the hydraulic unit by an automatic or spontaneous distribution of the steam supplied to the driving engine—may be applied in various ways and by various means without in the least departing from its spirit. One such application is illustrated, without 55 limiting my invention to the specific forms disclosed, in the accompanying drawings and the following description thereof. In the drawings:

Fig. 1 shows in diagrammatic elevation a 60 simple application of my method invention, in which the speed of the pump supplying fluid to the hydraulic unit is manually controlled and the variable pressure of steam in the pipe supplying the cylinder of the driving engine actuates a valve by which the

escape of fluid from the hydraulic unit is controlled.

Fig. 2 shows in diagrammatic elevation, on a reduced scale, a modification in the application of my invention in which the jack, being 70 set at or near the level of the derrick floor, may be given a much greater length than is permissible when it is placed in the position indicated in Fig. 1.

Fig. 3 is a diagram illustrating a valve such 75 as indicated at 28 in Fig. 1.

Referring to Fig. 1, numeral 5 indicates a hydraulic unit suspended by any preferred means from the travelling block 6. This unit comprises a cylinder 7, a piston 8 longitudinally slidable therein, a piston rod 9 rigidly affixed to said piston, and a stuffing box 10 through which the piston rod may reciprocate without substantial leakage.

A vent 11 provided at the upper end of 85 said cylinder for the maintenance of atmospheric pressure above the piston. The lower end of the piston rod is attached by any preferred means to the upper end 12 of the Kelley joint, this means including a 90 swivel (not shown) by which the hydraulic unit is relieved from rotation as the drill string rotates. A pipe or other connection 13 is provided at the lower end of cylinder 7 for the introduction and release of the fluid 95 by which the piston 8 is actuated.

The hydraulic unit above described is commonly known and used and I lay no claim 100 to its use other than as a means for putting my invention into application.

A steam actuated drilling engine of any preferred type is indicated at 14, this engine driving the rotary table 15 through suitable transmission apparatus diagrammatically illustrated at 39—39 in Fig. 1. The engine is 105 supplied with steam from a boiler or other source of supply not shown, through a main steam line 16 controlled by a valve 17 and communicating without further control with the drilling engine 14. This valve is used to 110 control the speed of the drilling engine by setting it at a preferred speed with a preferred pressure on the bit. As 17 is a throttling valve the pressure in line 16 below the valve is less than the pressure in the line 115 above the valve.

A branch pipe 18 controlled by a manually operated valve 19 communicates with pipe 16 above the control valve 17 and admits steam at boiler pressure to the steam cylinder 120 20 of the pump 21. This pump takes suction 23 on its water end 22 through suction pipe 23 from a tank 24, and discharges the water or other fluid through a flexible tube 25 to the hydraulic unit 5, Fig. 1, or the hydraulic unit 35, Fig. 2.

A branch line 26 connected into pipe 16 below the control valve 17 conducts steam to a weighted diaphragm 27, the movement of which controls the opening of a variable 130

orifice 28 placed in a pipe 29 which communicates with pipe 25 and is vented into tank 24. The connections between the diaphragm and the orifice should be such that the orifice closes as the pressure on the diaphragm increases. This orifice permits fluid to escape from pipe 25 and thus may relieve part of the pump discharge or, may allow water to flow out of the jack cylinder 7, according to the extent to which it is opened.

The orifice fitting 28 may be of the type illustrated in Fig. 3 in which 28 is a body similar to that of the well known globe valve, having a partition 42 in which is formed a seat 43 adapted to be closed by a tapered plug 44. To this plug is attached a pin 45 passing through a stuffing box 46. The diaphragm chamber 27 is provided with a flexible diaphragm 40 and the closed vessel thus formed is so spaced from the fitting, as by the straps 41, that the pin 45 bears lightly on the diaphragm when the chamber is under atmospheric pressure and the plug is fully withdrawn. In this position of the plug 25 an annular passage is left between plug and seat for the passage of liquid.

The diaphragm chamber is filled with steam from pipe 26 and as the steam pressure in this pipe increases the diaphragm is distended, advancing the tapered plug into the seat and thus restricting the annular opening.

It is desirable in practice to use a more refined type of valve, the fitting shown being illustrative only. Preferably the valve should be so constructed that the fluid pressure transmitted through pipe 29 to the under side of the plug is balanced within the valve and does no come against the diaphragm. Many such valves are well known and understood.

Fig. 2 shows an application of my invention in which the hydraulic jack, being set on or near the level of the derrick floor, may be given a much greater length than is permissible when it is placed in the position indicated in Fig. 1, between the drill string swivel and the travelling block.

Referring to Fig. 2, the outline of a derrick is indicated at 29 and the drilling line at 30. This line is spooled at one end on the winding drum 31 and at the other on the calf wheel drum 32, passing from the latter over a fixed sheave 33, then through a sheave moved by the piston of hydraulic unit 35, and is rove through the crown block 36 and the travelling block 37 in the usual manner. The pipe 38 communicating with the interior of the jack is connected to the pipe 25 indicated in Fig. 1. This jack lifts tools by a downward movement of the piston instead of by an upward movement as in the jack shown in Fig. 1. This arrangement is a generalization of current practice in rigging and is no part of my present invention ex-

cept insofar as it is used in connection with my method of control.

The above apparatus functions as follows. The pump, taking steam from a point above the control valve 17, is maintained at a constant speed by hand regulation of valve 19. With hand regulation as shown the stroking of the pump must be timed at frequent intervals to maintain a constant rate of discharge through pipe 25. Better control over the discharge of the pump may be maintained by interposing in pipe 25, at any point between the pump and the junction of pipe 25 with the pipe 29, a sensitive fluid meter by which the actual discharge of the pump may be timed, thus eliminating any question as to internal slip in the pump.

Still better regulation of pump discharge may be automatically obtained by substituting for the simple type of pump shown a fly-wheel or engine driven pump, the speed of which may be controlled by a governor.

It will be understood that a constant delivery by the fluid pump is not essential to the proper functioning of the modification here described, as the throw of the variable orifice 28 should be sufficient to take care of variation both in dead weight of drill string and in pump delivery, each of which is immediately reflected in a change in bit pressure. Control of bit pressure will, however, be much more sensitive if the orifice control is not required to compensate a wide variation in pump delivery.

When, from any cause, the bit bears too heavily on the bottom of the hole, the engine 14 slows down and the steam pressure in the portion of pipe 16 which lies below the control valve 17 correspondingly increases. This increased pressure is transmitted through pipe 26 to diaphragm 27 which, by its movement thus caused, partially closes orifice 28. Leakage from the hydraulic unit being thus restricted, the piston 8 rises and thus relieves the bit pressure.

The basic principle of my present invention is as follows. Steam being applied simultaneously, through a control valve or other pressure reducing device, to an engine driving the rotary table and to a means for controlling the amount of fluid permitted to escape from a hydraulic jack, a reduction in speed of the engine builds up an increased pressure of steam which is transmitted to the orifice control, partially closing it and causing an upward movement of the jack piston. This movement of the piston lifts the bit through such distance as to cause it to revolve more freely, thus setting in train the reverse of the above movements, by which the bit is slightly lowered. By minute and rapid alteration in the direction of these movements, the bit is fed into the hole as made, while being maintained in substantially the

most effective contact with the bottom of the hole.

I claim as my invention:

1. An apparatus for controlling the pressure exerted by a rotary well-drilling bit on the bottom of the hole being drilled, comprising: a steam-actuated engine adapted to rotate said bit; a hydraulic jack adapted to raise and lower said bit; means adapted to force fluid into said jack for raising said bit; an orifice communicating with said jack adapted to permit escape of fluid therefrom for lowering said bit; a steam-actuated means adapted to control the area of said orifice, and a means for admitting a flow of steam under pressure to a means of communication between said engine and said orifice-controlling means, whereby said engine is actuated and the area of said orifice is simultaneously controlled.
2. An apparatus for controlling the pressure exerted by a rotary well-drilling bit on the bottom of the hole being drilled, comprising: a steam-actuated engine adapted to rotate said bit; a hydraulic jack adapted to raise and lower said bit; means adapted to force fluid into said jack for raising said bit; an orifice communicating with said jack adapted to permit escape of fluid therefrom for lowering said bit; a diaphragm means adapted to control the area of said orifice, and a means for admitting a flow of steam under pressure to a means of communication between said engine and said diaphragm means, whereby said engine is actuated and the area of said orifice is simultaneously controlled.
3. In an apparatus for controlling the feed of a rotary well-drilling bit which includes a steam engine rotating said bit, a pipe supplying steam to said engine, a valve in said pipe, a hydraulic jack raising and lowering said bit, a means for supplying fluid to said jack for raising said bit and an orifice for permitting the escape of fluid from said jack for lowering said bit; a means for controlling the escape of fluid from said jack, comprising: a steam-actuated means adapted to vary the area of said orifice and a means of communication between said steam-actuated means and that portion of said steam-pipe situated between said valve and said engine.
4. In an apparatus for controlling the feed of a rotary well-drilling bit which includes a steam engine rotating said bit, a pipe supplying steam to said engine, a valve in said pipe, a hydraulic jack raising and lowering said bit, a means for supplying fluid to said jack for raising said bit and an orifice for permitting the escape of fluid from said jack for lowering said bit; a means for controlling the escape of fluid from said jack, comprising: a diaphragm means adapted to vary the area of said orifice and a means of communication between said dia-

phragm means and that portion of said steam-pipe situated between said valve and said engine.

In witness that I claim the foregoing I have hereunto subscribed my name this 19th day of June, 1929.

PHILIP JONES.
